GOLF GAME

Alvin R. Thomas, Chicago, Ill.

Application January 30, 1931, Serial No. 512,329

9 Claims. (Cl. 273—32)

This invention relates to improvements in golf games of the type to be used in the home or out-doors, where putting practice may be had requiring about the same stroke that is required on the golf course, and which may be played by a number of people at the same time.

An important feature of my invention is to construct a golf game that is portable, strong and durable, which may be manufactured at a low cost, and which may be readily assembled or taken apart for shipping purposes.

Another object is to provide a golf game having a plurality of ball-rolling surfaces, some of which have cup simulating openings therein, and a ball-rolling surface having an arched back wall to cause a ball played up to the back wall to loop around an inclined plate and thus roll forward to a ball collector.

A further object is to construct a golf game having a plurality of inclined ball rolling surfaces provided with cup simulating openings and chutes or runways, communicating with the openings, to direct a ball from the openings to a ball collector.

A still further object is to provide a cushioned top rail overhanging the inclined surfaces and a baffle or deflector plate fixed to the top rail over the openings in the inclined surface, so that a ball played up to the baffle or deflector will rebound through the opening in the inclined surface, while a ball played clear of the baffle will strike the cushioned rail, rebound down the incline and return to the player.

In the drawings forming a part of this invention,

Figure 1 is a top plan view of the device embodying my invention;

Fig. 2 is a front elevation of the device;

Fig. 3 is a cross-sectional view taken on line 3—3 of Fig. 2;

Fig. 4 is a perspective view of the device, as viewed from the back;

Fig. 5 is a cross-sectional view taken on line 5—5 of Fig. 2;

Fig. 6 is a cross-sectional view similar to Fig. 5 illustrating a modified form of guard for the ball collector, and

Fig. 7 is a cross-sectional view taken on line 7—7 of Fig. 2.

Referring to the drawings, 10 designates a main central portion having side walls 11 and 12, respectively, and an inclined surface or bottom wall 13 extending rearwardly into an arched back wall 14 and forward into a top wall 15. An inclined plate 16 is fixed to the side walls 11

and 12 and extends from the front thereof to a point 17 spaced from the arched back wall 14 to form a passage therebetween.

A ball collector 18 having a receiving end 18a is movably supported at the forward end of the inclined plate 16 by means of a pair of arms 19 pivotally mounted on the side walls 11 and 12. Spaced from the inclined plate 16 and aligned with the side walls 11 and 12 is a ball stop 20 having a pair of pins 21 on either side engaging bayonet slots 22 in the side walls, so that the ball stop 20 may be readily removed.

When a ball is played up the inclined surface 13 and has enough momentum to be carried around the arched back wall 14, it will strike the ball stop 20, fall on the inclined plate 16 and roll into the ball collector 18 through the receiving end 18a. The arched back wall 14 is provided with a proper curvature to cause the ball to be carried around the end 17 of plate 16 and move forwardly along a line represented substantially by the arrows 14; so as to strike plate 20 and drop upon the forward end of inclined plate 16.

Side walls 11 and 12 each have an opening 11a 80 therein, the bottom of which is aligned with the rearward end of the inclined plate 16.

A pair of arcuate plates 23 and 24 are provided with side walls 23a and 24a secured thereto. The inner or face ends of plates 23 and 24 are provided with cleats 25 adapted to engage U-shaped cleats 26 disposed on the outside of walls 11 and 12 of the main central portion 10.

Arcuate plates 23 and 24 are thus removably held in an inclined position on the side walls. 90 However, supporting brackets 27 are removably secured to cleats 28—28 on the arcuate plates and to the cleats 29—29 on the side walls 11 and 12 to lock the arcuate plates rigidly in position.

Inclined arcuate plates 23 and 24 are provided with cup simulating openings 30 and 30, respectively, adjacent their upper ends, and an overhanging rail or stop 32—32 extending the entire length of the top edge. A baffle or deflector plate 33 is secured to the overhanging rail above each of the cup simulating openings in the inclined arcuate plates. These baffles or deflector plates 33 are preferably dished or cupped as at 34, see Fig. 3, so that when a ball is played up the inclined arcuate plates 23—24 to the deflector plate 33, the dished or cupped portion 34 will cause the ball to rebound through the cup simulating opening 30.

On the rear of the arcuate plates 23—24, I provide U-shaped cleats 25a adapted to receive L- 110

shaped cleats 35 rigidly secured to chutes 36, which have bottom walls 37 and curved back walls 38. These chutes 36 communicate with the cup simulating openings 30 to direct a ball received from the latter through opening 11a in the side walls 11 and 12 onto the inclined plate 16 to the ball collector 18.

A cushion 39 of relatively resilient material is fixed to the underside of the overhanging rails 10 or stops 32—32 on either side of baffle or deflector plates 33—33 to cause a ball to rebound down the inclined arcuate plates 23—24 when a ball is played up the incline and clear of the baffles.

The ball-rolling surfaces 13—14 and 23—24 15 and the chutes 36 and the inclined plate 16 and ball collector 18 may be covered with a thin layer of felt or other suitable material, so that the balls may roll very silently to the ball collector, thereby eliminating metallic-like sound caused by 20 the rolling of a ball.

In Fig. 6 is illustrated a modified form of ball stop designated as a whole as 40. This ball stop 40 consists of a bail 41 of a substantially U-shape having side members 42 and a front member 43. The free ends of the side members 42 are turned inwardly and downwardly as at 44, to engage bayonet slots 45 in the side walls 11 and 12. A screen or wire cloth 46 is fixed to the bail 41 and adapted to surround the ball collector 18 so 30 that a ball played up the incline 13 around the arched back wall 14 to the screen 46 will be directed to the ball collector.

Fixed to the top wall 14 of the main unit 10 is a handle 47 to facilitate the handling or placing 35 of the device to be played when it is assembled.

It will be seen that with a device of the character as above set forth three players may play the game at the same time requiring skill and dexterity on the part of the players.

40 One of the advantages of the device disclosed herein is that the balls played up to the inclined walls 23 and 24 and not entering openings 30 are caused to be returned down the incline in the direction of the player, thereby not requiring the player to walk needlessly about to recover the balls driven during the play. Side walls 23a and 24a assure the balls a proper direction of return and prevent them from rolling over the sides or being deflected out of the path of play. The unit 45 is self-contained in a simple and inexpensive structure and furnishes a variety of interesting putt-shots requiring considerable skill and accuracy.

I contemplate as being included in these improvements all such changes, variations and departures from what is thus specifically illustrated and described herein as fall within the scope of the appended claims.

1 claim:

60 1. In a golf game comprising, in combination, a plurality of inclined ball rolling surfaces having an opening for receiving a ball in simulation of a golf cup at their upper ends, a ball collector exteriorly of said inclined surfaces, an inclined plate 65 coaxing with one of said inclined ball rolling surfaces to direct a ball to the ball collector, and chutes communicating with the other openings in the inclined surfaces to direct a ball when played through said openings to the ball collector.

70 2. A golf game comprising a unit adapted to be placed on a relatively smooth surface and having a plurality of inclined ball rolling surfaces with cup simulating openings adjacent the upper ends of said inclined surfaces to provide ball 75 rolling surfaces as an approach to the cup simu-

lating openings, a ball collector positioned centrally of said unit, chutes communicating with said cup simulating openings to direct a ball from the openings to said ball collector, stop means adjacent the upper end of said inclined surfaces extending the entire length thereof, and baffle plates fixed to said stop means and positioned above the openings in said inclined surfaces to cause a ball to rebound through the opening when the ball is played up to the baffle.

3. A golf game comprising a unit adapted to be placed on a relatively smooth surface and provided with an inclined ball rolling surface centrally thereof, an inclined arcuate ball rolling surface adjacent either side thereof and having their forward edges aligned with said central inclined surface, a cup simulating opening adjacent the upper end of said inclined arcuate surfaces, a ball collector positioned above and forwardly of said central inclined surface, an inclined plate parallel with and spaced above said central inclined surface to direct a ball to said ball collector, chutes communicating with said cup-simulating openings and said inclined plate to direct a ball from said openings to said ball collector, and stop means coaxing with said ball collector to direct the ball to the ball collector.

4. A golf game comprising a unit having side walls with openings therein adapted to be placed on a surface and provided with a centrally located inclined ball rolling surface extending rearwardly into an arched back wall, a top wall, an inclined plate interposed between the inclined ball rolling surface and the top wall fixed to the side walls below the openings in the side walls 110 and spaced from the back wall to form a passageway for a ball therebetween, a ball collector positioned forwardly of the inclined plate, a pair of inclined arcuate ball-rolling surfaces each having an end wall and provided with means for 115 removably securing them with their front edges aligned with the inclined surface, cup simulating openings adjacent the upper edge of said inclined arcuate surfaces, chutes removably secured to the rearward side of the inclined arcuate ball 120 rolling surfaces and communicating with said cup simulating openings to direct a ball through the opening in the side walls down the inclined plate to the ball collector.

5. A golf game of the character described comprising a main member having side walls with openings therein, an inclined bottom wall merging into an arched rear wall, a top wall, an inclined plate fixed to the side walls below the openings in said side walls and spaced from the arched rear wall and the inclined bottom wall to form a passageway for a ball around said inclined plate, a ball collector extending forwardly of the inclined plate on said main member, a pair of inclined arcuate plates having cup simulating openings at the upper end thereof, chutes removably secured to the inclined arcuate plates communicating with the cup simulating openings and the openings in the side walls to direct a ball from the cup simulating openings to the ball collector, and bracket reinforcing means between the inclined arcuate plates and the side walls to removably secure them together.

6. A golf game of the character described comprising a central member having side walls with openings therein, an inclined bottom wall merging into an arched rear wall, a top wall, an inclined platform secured to the side walls and having its rearward end spaced from the arched rear wall to form a passageway for a ball therebe-

- tween, a ball collector extending forwardly of the inclined platform, ball stop means coacting with the inclined platform and said ball collector to direct a ball to the ball collector, a pair of inclined arcuate plates having cup simulating openings at the upper end thereof and secured to the central member with their forward edges aligned with said central member, and chutes communicating with said cup simulating openings and the openings in said side walls to direct a ball from said cup simulating openings to the ball collector.
7. In a golf game comprising, in combination, a plurality of inclined ball rolling surfaces having an opening for receiving a ball in simulation of a golf cup at their upper ends, a ball collector, an inclined plate coacting with one of said inclined ball rolling surfaces to direct a ball to the ball collector, chutes communicating with the openings in the inclined surfaces to direct a ball when played through said openings to the ball collector, and ball stop means overhanging the inclined ball rolling surfaces adjacent their upper ends, said ball stop means causing the ball to rebound down the inclined ball rolling surface to return to the player when the ball is played on the inclined surface and clear of the openings.
8. In a golf game comprising, in combination, a plurality of ball rolling surfaces having cup simulating openings at their upper ends, a ball collector, an inclined plate coacting with one of said inclined ball rolling surfaces to direct a ball to the ball collector, chutes communicating with
- the cup simulating openings in the other inclined surfaces to direct a ball from the openings to the ball collector, ball stop means overhanging the inclined surfaces adjacent their upper ends, deflector plates fixed to said ball stop means and extending forwardly over said cup simulating openings so as to form a deflector for a ball when the ball is played up to the deflector plates, and a cushion extending the entire length of the ball stop means on either side of the deflector plates causing a ball played up the inclined ball rolling surfaces and clear of the deflector plates to strike the cushion and rebound down the inclined surface to the player.
9. A golf game comprising a unit adapted to be placed on a relatively smooth surface and having a plurality of inclined ball rolling surfaces with cup simulating openings adjacent the upper ends of said inclined surfaces to provide ball rolling surfaces as an approach to the cup simulating openings, a ball collector positioned centrally and extending forwardly of said unit, chutes communicating with said cup-simulating openings to direct a ball from the openings to said ball collector, ball stop means overhanging the inclined surfaces adjacent their upper ends, and deflector plates fixed to said ball stop means and extending forwardly over said cup simulating openings so as to form a deflector for a ball when the ball is played up to the deflector plates, said ball stop means returning the ball when the ball is played up the arcuate inclined surfaces and clear of the deflector plates.
